RAZOR BLADE HONING MACHINE

Gerret J. Southland and Joseph Casper,
Blaine, Wash.

Application May 8, 1933, Serial No. 669,902

1 Claim. (Cl. 51—159)

Our invention relates to improvements in razor blade honing machines and has for an object to provide a hand-operated machine of this type of simple and inexpensive design yet 5 having the accuracy of adjustments and operation of more complicated and expensive machines.

Other objects of our improvement will appear as the description proceeds.

We attain these and other objects of our improvement with the mechanism illustrated in the sheet of drawing accompanying this specification and forming a part thereof in which Figure 1 is a plan view of our razor blade honing machine, Fig. 2 is a side elevation of Fig. 1, Fig. 3 15 is a plan view of the oscillative blade clamp, drawn on a larger scale, Fig. 4 is an edge elevation of Fig. 3, and Fig. 5 is a fragmentary portion of Fig. 2 drawn in dotted outline on a larger scale showing the moving parts in two characteristic 20 positions thereof.

Similar characters indicate similar parts throughout, and certain parts are broken away to show other parts hidden thereby.

With more particular reference to the indicated parts: A frame is formed from a piece of sheet metal having the front end 6, the rear end 7 and the bottom 8. The false bottom 9 is fastened in the said frame parallel with the bottom 8 and spaced apart therefrom. The bearing 25 brackets 10, 10 are fastened to the rear end at the top corners thereof having the aligned bearings 11, 11. The two guide and clamping rods 12, 12 are extended through aligned holes in the ends of the frame near the top corners thereof 30 and are disposed parallel with each other and at right angles with the frame ends. These rods are provided with heads, threaded ends and nuts thereon whereby they are used to retain the frame ends in parallel relation. There are four holes 35 through the bottom 8 two of which are shown at 13, 13. Aligned with the holes 13 are tapped holes in the false bottom 9 in which are engaged the four adjustment screws 14, 14, 14, 14. Between the ends 6 and 7 and the rods 12 is disposed the hone 15 bearing on the upper ends of the four screws 14. The clamping screw α 15 is engaged in a tapped hole through the back end 7 disposed to bear on the rear end of the hone 15 to clamp the same between the front 40 end 6 and the said screw α 15.

The pair of bearing slide blocks 16, 16 are mounted for reciprocation on the rods 12, 12 and have bearing holes therein which are aligned when the blocks are opposite each other. The 45 rockshaft 17 is mounted for oscillation in the said bearing holes in the slide blocks 16, 16. The central portion of the shaft 17 is flattened and has fastened thereon the base clamp plate 18 which has the two hinge ears 19, 19 on one end 50 and the bent-over catch 20 on the other end

thereof. The top clamp plate 21 has the hinge ear 22 on one end, the two-part, bent-over latch 23, 23 and the handle 24 on its other end. The hinge ears 19, 19 and 22 have aligned holes therein through which is extended the hinge pin 23 joining the same in hinge relation, providing for the plate 21 to oscillate on the said hinge and disposing the latch 23, 23 in close frictional relation with the catch 20 when the clamp plates 18 and 21 are in close relation with the space 27 10 therebetween. The studs 25, 25 on the base plate 18 extend through the holes 26, 26 in the plate 21 when the said plates are engaged by the latch 23 on the catch 20.

When the hinged plate 21 is raised free of the 15 base plate 18 a razor blade 28, having holes therein through which the studs 25 may be extended, may be placed on the base plate 18 with the said studs extending through the said razor blade holes, and by returning the plate 21 to engage the latch 23 with the catch 20 the said blade is engaged in the narrow space 27 by the said studs and firmly clamped between the plates 18 20 and 21.

The shaft 29 is mounted for revolution in the 25 bearings 11, 11 and has the cranks 30 and 31 on the ends thereof. The said cranks are of equal length, opposite each other and disposed adjacent the said bearings in the same plane. The ends of the cranks 30 and 31 are bent outward at right angles providing the long crank pin 32 and the short crank pin 34 respectively. The crank pin 32 is extended through a hole in one end of one of the side bars 35 and also through a hole in crank handle 33 and has its outer end 30 upset to retain the bar and handle in place thereon. The crank pin 34 is extended through a hole in one end of the other side bar 35 and has its outer end upset to retain the bar in place 35 thereon. The side bars 35, 35 are of equal 40 length and have holes through their other ends through which are extended the ends of the shaft 17. There are two spring cranks 36, 36 each having a hook 37 on one end and a hole 45 through the other end. These spring cranks are mounted on the outer ends of the shaft 17 in a manner whereby they are firmly fastened upon the said shaft to oscillate therewith, as, for instance, being pressed thereon when expanded by 50 heat. When in place on the shaft the spring cranks 36, 36 are in the same plane and opposite each other and also, preferably, in the plane of the base plate 18.

Several spaced tapped holes 38 are in the side 55 bars 35, 35 and in one thereof in each bar is engaged a stud 39 having an annular groove therein. A helical spring 40 is fastened to the hook 37 on each of the spring cranks 36 and to the stud 39 on each of the side bars 35 to react therebetween 60

and oscillate the blade holder 18, 21 as herein-after described.

The hone 15 is set in the desired position with its top surface parallel with the plane of the rods 12 and at a distance beneath the shaft 17, determined by the beveled cutting edges of the blade 28, by adjusting the screws 14, the kerfs of which are accessible to a screw-driver extended through the holes 13. Having set the hone in the suitable position, it is retained therein with the clamping screw a15.

The cranks 30 and 31 may be revolved in either direction, but, preferably, they are turned in the direction indicated by the arrows. In Figs. 1 and 2 the farthest forward positions of the blade 28, the blade holder 21, the slide bearings 16, the cranks 30 and 31, the handle 33 and the springs 40 are shown in solid lines, while the farthest rearward positions of these instrumentalities are shown in dotted lines and indicated by the primes of the numbers indicating the said forward positions thereof.

In Fig. 2 the spring crank 36 is inclined downward, causing the blade 28, not shown in Fig. 2, 25 to bear with its forward edge on the hone 15 and be retained in resilient contact therewith by the reaction of the spring 40. This spring reaction tends to retain the said blade edge in contact with the hone because the spring 40 is below the shaft 17 although the side bar 35 is parallel with the rod 12. In Fig. 5 the crank 30, when at its dotted position at 30', is about 75° in advance of its position shown in Fig. 2. At this crank position the slide bearing 16, the shaft 17, the side bar 30, the spring crank 36, the handle 33 and the spring 40 are in positions indicated by the seconds of the said designating numbers, disposing the blade 28 at 28'' in a position less than one half of its operative reciprocative movement from its most forward position over the hone 15 and tilted with its rear edge bearing on the said hone. By continuing the crank revolution in the same direction till it reaches its position at 30' in Fig. 1 the blade will have reached its farthest rearward 45 position at 28' and its rear cutting edge will have remained in contact with the hone from its illustrated position at 28'' in Fig. 5. That is, the movement of the crank from its position at 30 in Figs. 1 and 2 to its position at 30'' in Fig. 5, not only carried the blade from its position at 28 in Fig. 1 to its position at 28'' in Fig. 5 but also tilted the blade to transfer its contact with the hone from its front to its rear edge. This tilting of the blade was due to the upward movement of the 50 stud from its position at 39 in Figs. 1 and 2 to its position at 39'' in Fig. 5, causing the spring 40 to pass above the shaft 17.

By turning the crank 30 from its position at 30' in Fig. 1 to its position at 30''' in Fig. 5 it will 60 have moved through an angle of about 75° and carried the blade from its position at 28' to its position at 28''' and at the same time have moved the slide bearing 16, the shaft 17, the side bar 35 the spring crank 36, the stud 39 the handle 33 65 and the spring 40 to the thirds of these designating characters.

As stated above, when in the position at 28', the blade was tilted to cause its rear edge to bear on the hone, but by moving the crank from its 70 position at 30' to its position at 30''' the springs 40 pass beneath the shaft 17 and tilt the blade causing its front edge to bear on the hone. By continuing the forward revolution of the cranks 30 and 31 from their said position when the crank 75 30 is at 30''' till they reach their position shown

in solid lines in Figs. 1 and 2, the blade 28 is moved forward to the front edge of the hone with its front edge in contact therewith.

It is now clear that continuous revolution of the cranks 30 and 31 will cause the blade 28 to move forth and back over the hone intermittently changing its edge contacting therewith twice for each revolution of the said cranks.

In practice, when the blade is sufficiently honed on one side of its cutting edges the top clamp plate 21 is lifted by pulling upward on the handle 24 and the blade is reversed in the clamp and again clamped therein by returning the plate 21 to its clamping position. Then the honing of the edges contacting with the hone is carried forward as before till the sharpening of the blade is completed. For, in practice, it has been found that the sharpening of razor blades on the described honing mechanism provides a good cutting edge without the usual subsequent stropping 20 thereof.

The pressure provided by the springs 40 retains the edge being sharpened in contact with the hone except at the periods when the blade is being tilted by operation of added pressure from the springs. 25 It is important that the pressure which retains the edge being sharpened in honing contact be suitable.

With this in view a few adjustments of this pressure may be made by engaging the studs 39 30 in others of the tapped holes 38 than those in which they are shown as being engaged.

Although a razor blade clamp suited for holding but one of the well-known types of razor blades is shown and described, it is evident that 35 our clamp may be adapted for any of the usual shapes of razor blades.

Only one mechanical reduction of our invention is herein disclosed, yet any variation therefrom which retains the essence of our invention is 40 within its purview, and we desire to have it so understood.

Having thus disclosed our invention, what we claim as new therein and desire to secure by Letters Patent is,—

A razor blade honing machine including, a hone, a pair of parallel slideway rods, means to retain the operative surface of the said hone and the said slideway rods in parallel planes, a bearing block mounted for reciprocation on each of the said slideway rods, a razor blade clamp adapted to releasably retain a razor blade, aligned rock-shaft ends fastened on the ends of the blade clamp mounted in bearings in the said bearing blocks for oscillation and protruding beyond the said blocks, bearing brackets fastened to the said slideway rods having aligned bearings therein parallel with the said rockshaft ends, a crank shaft mounted in the said bracket bearings, equal opposite driving cranks fastened on the ends of the said crank shaft disposed in the same plane, a crank pin on each of the said cranks, two equal sidebars each having one end thereof mounted on one of the said rockshaft ends and the other end thereof mounted on one of the said crank pins, two equal spring cranks each fastened on one of the said rockshaft ends to oscillate the same disposed in the plane of the said blade clamp, and a tension spring fastened to the outer ends of each of the spring cranks and to each of the said sidebars reacting to tilt the said blade clamp by oscillating the said spring cranks as the said sidebars reciprocate and oscillate.
